CLAIM

The ornamental design for an arc shaped vacuum pouch, as shown and described.

DESCRIPTION

FIG. 1 is a perspective view of an arc shaped vacuum pouch showing our new design;

FIG. 2 is a top view of the design shown in FIG. 1, wherein the bottom view is identical or a mirror image thereof;

FIG. 3 is a front view of the design shown in FIG. 1;

FIG. 4 is a rear view of the design shown in FIG. 1; and,

FIG. 5 is a right side view of the design shown in FIG. 1, wherein the left view is identical or a mirror image thereof.

The broken lines shown in the drawing are for illustrative purposes only and form no part of the claimed design.
